Patented June 28, 1960

188,294

HEAVY DUTY WHEEL BALANCING UNIT

Wilbur C. Rexroat, 141 Candler Road SE., Atlanta, Ga.

Filed June 19, 1958, Ser. No. 51,426

Term of patent 14 years

(Cl. D55—1)

FIG. 1

Des. 188,294

PAGE 2

FIG. 2

FIG. 3

Fig. 1 is a perspective view of a heavy duty wheel balancing unit showing my new design.

Fig. 2 is an end view of the wheel balancing unit shown in Fig. 1.

Fig. 3 is an end view of the wheel balancing unit shown in Fig. 1, taken from the end opposite the end shown in Fig. 2.

The side of the unit not shown is the same as the side shown.

I claim:

The ornamental design for a heavy duty wheel balancing unit, substantially as shown and described.
